UNITED STATES PATENT OFFICE.

ANTONI CUDOSKY AND LUDWIKA CUDOSKY, OF PASSAIC, NEW JERSEY.

FIRE-ALARM-BOX ATTACHMENT.

1,164,786.

Specification of Letters Patent. Patented Dec. 21, 1915.

Application filed May 26, 1915. Serial No. 30,686.

To all whom it may concern:

Be it known that we, ANTONI CUDOSKY and LUDWIKA CUDOSKY, subjects of the Czar of Russia, residing at Passaic, in the county 5 of Passaic and State of New Jersey, have invented certain new and useful Improvements in Fire-Alarm-Box Attachments, of which the following is a specification.

This invention relates to certain new and 10 useful improvements in fire alarm box attachments.

The primary object of this invention is to provide a device for reducing the number of false fire alarms in fire alarm systems 15 where street operated alarm boxes are employed.

A further object of the invention is to provide the usual fire alarm box with an attachment whereby the arm of any person 20 operating the alarm is securely handcuffed until released by an official of the fire department.

A still further object of the invention is to provide an automatic wrist engaging device upon the door of a fire alarm box which 25 being manually set by the firemen, is automatically released by any person turning in an alarm so that any person who turns in a false alarm will be retained at the alarm 30 box until released or arrested by the proper official.

With these general objects in view and others that will appear as the nature of the invention is better understood, the same consists in the novel combination and arrangement of parts hereinafter more fully described, illustrated in the accompanying drawings, and pointed out in the appended claims.

In the drawings forming a part of this application and in which like-designating characters refer to corresponding parts throughout the several views, Figure 1 is an interior elevational view of the door of 45 a fire alarm box provided with the present device, the elements shown in their normal unlocked position. Fig. 2 is a similar view showing the elements in their locked positions. Fig. 3 is an interior view of a fire 50 alarm box provided with the present device, the door being open. Fig. 4 is a horizontal sectional longitudinal view through the fire alarm box when closed. Figs. 5 and 6 are perspective views of the two wrist-engaging

means, and Figs. 7 and 8 are perspective 55 views of the locking racks employed therewith.

Referring more in detail to the drawings, the present invention is illustrated in connection with a fire alarm box 10 having a 60 hinged door 11, the latter being adapted to be secured in its closed position by means of a suitable hasp 12' engaging over a staple 13' within which a padlock (not shown) 65 may be inserted.

It is to be noted that the alarm boxes 10 are provided in any number in the fire alarm system and that a central alarm may be sounded by operating any one of the boxes, such operation being effected in any 70 desired and well-known manner, such as by completing an electric circuit between the terminals 12 and 13 provided within the boxes, such a completion of the circuit being accomplished by swinging a switch lever 14 75 by means of a pivoted knob 15 so as to bridge the said terminals.

The box door 11 has a front opening 16 therein which is normally covered by a slide 17 pivoted as at 18 within the box and resiliently retained in its closed position by means of a coil spring 19. A turn knob 20 is secured upon the outer end of the slide pivot 18 exteriorly of the door 11 whereby the slide may be opened to the position illustrated in Fig. 2 against the action of the spring 19 and thus allowing the hand to be inserted through the front opening 16 for grasping the knob 15 and lowering the switch lever 14 for sending in a fire alarm. 90 The slide is guided in its movement by having a slot 21 formed therein for the reception of a pin 22 secured to the door 11.

A plate 23 is arranged within the door 11 slightly spaced from the front wall thereof 95 and has an opening 24 in alignment with the door opening 16. A wrist engaging yoke 25 is slidably mounted between the plate 23 and adjacent the side of the door and has its spaced ends 26 attached to compression 100 springs 27, the opposite ends of the said springs being secured as at 28 adjacent the opposite end of the door. A rack 29 is longitudinally positioned within the door being provided with a stop shoulder 29' adjacent its inner end and with teeth 30 upon its upper face. A latch link 31 is pivoted to a cross bar 32 of the yoke 25 and is posi-

tioned in abutting engagement with the said lug 29 when the yoke 25 is normally arranged unobstructing the door and plate openings and at which time the springs 27 are under tension.

5 A hook shaped wrist engaging member 33 has a curved end 34 slidably arranged rearwardly of the plate 23 and is slidably positioned underlying the yoke bar 32 and within a strap 35 secured to the door which strap also acts as a guide for the link 31.

10 A rack 36 is longitudinally secured within the door 11 and has a stop notch 37 adjacent the outer end and a plurality of teeth 38 upon its upper face. The said hook 33 has an angular end 39 adapted for seating within the notch 37 of the rack 36 when the hook end 34 is withdrawn from the door opening. A tension spring 40 is secured between the hook end 39 and the bracket 41 carried by the door and upon disengaging the hook from the notch 37, the spring draws the hook end 39 over the rack teeth 38 until the said end 39 seats within a retaining notch 42 adjacent the free end of the said rack 36.

15 The elements are normally positioned as shown in Fig. 4 and with the door lock closed, the door carried elements being in the position illustrated in Fig. 1 of the drawings, and the box carried alarm actuating means being in the positions illustrated in Fig. 3. A post 43 mounted within the alarm box, has a rocker lever 44 mounted thereon which is pivotally connected to the free end of the switch lever 14 by a connecting link 45. When the elements are in their normal set positions, the projecting spring 40 of the hook 33 is under tension as 20 well as the actuating springs 27 of the yoke 25 and an operating finger 46 is provided upon the end of the rocker lever and underlies the angularly projecting end 47 of the yoke link 31, while a downwardly projecting lug 48 of the hook member 33 is slightly spaced above the said link end 47.

25 A person for instance who desires to turn in a false alarm will turn the outside knob 20 and open the slide 17 and insert his hand through the door opening 16 and plate opening 24 and will grasp the switch knob 15 and turn the same for closing the switch of the alarm circuit, while simultaneously therewith, the rocker lever 34 will be pivotally moved for elevating the lever finger 46. This upward movement of the finger 46 raises the free end of the yoke link 31, thereby releasing the same from the end shoulder 29' of the rack 29 and whereby the link end 47 will ratchet over the rack teeth 30, the yoke 25 being moved inwardly of the door opening by means of the springs 27. The yoke members will thus be positioned as shown in Fig. 2 and the link end 47, 30 thereof, will engage one of the rack teeth 30

35 preventing any return movement of the yoke. The upward disengaging movement of the said link end 47, engages the bottom of the hook lug 48, thus elevating the hook end 39 and disengaging the same from the notch 37 of the rack 36, whereupon the spring 40 forces the hook end 39 over the rack teeth 38 until the said end seats within the forward stop notch 46 which thereby locks the hook in its projected position as 35 illustrated in Fig. 2 and with the curved end 44 thereof within the margins of the door opening. The arm of the operator of the alarm extending through the door opening at the time of the automatic releasing of the yoke and hook as just described, it will be understood that the arm or wrist of the operator is received between the said hook and yoke and these members being locked in their projected positions as shown in Fig. 2, 40 the operator of the alarm will be unable to withdraw his hand from the door and must therefore remain a prisoner until some authorized official releases his said hand by opening the door 11, and resetting the hook 45 and yoke.

45 While the form of the invention herein shown and described is what is believed to be the preferred embodiment thereof, it is nevertheless to be understood that minor changes may be made without departing from the spirit and scope of the invention as set forth in the claims.

50 What is claimed as new is:—

1. In combination with an alarm box having a lockable door, the said door being provided with an arm entrance opening, alarm actuating means swingingly positioned within the said box, a rocker arm pivoted within the said box, a pivotal connecting link between the said rocker arm and actuating means, a yoke longitudinally slidably transversely of the said opening and within the said box, resilient operating means for the said yoke, a retaining link for the said yoke having an angularly projecting end, a hook slidable transversely of the said opening and positioned within the borders of the said yoke, an angular latch end upon the said hook, resilient projecting means attached to the said latch end, and a downwardly projecting lug upon the said hook overlying the said yoke catch when the elements are normally positioned, the yoke catch normally lying within the releasing path of movement of the said rocker lever. 100

105 2. A fire alarm box having a hand entrance opening in the door thereof, a normally closed pivoted slide for the said opening, a knob operated alarm circuit closure within the said box, a yoke and hook transversely slidable in opposite directions with respect to the said opening, oppositely impelling resilient actuating means for the said yoke and hook, latch retaining means 110

for the said yoke and hook, the retaining means for the said hook lying within the releasing path of movement of the yoke retaining means, and automatic trip connections operatively attached to the said circuit closure and having a path of movement in the same plane as the yoke retaining means.

In testimony whereof we affix our signatures.
